UNITED STATES PATENT OFFICE.

WILLIAM H. UNKE AND OTTO C. UNKE, OF MILWAUKEE, WISCONSIN.

DESIGN FOR A CASING FOR HORN-BLOWERS.

41,861.

Specification for Design.

Patented Oct. 24, 1911.

Application filed August 20, 1910. Serial No. 578,248. Term of patent 14 years.

To all whom it may concern:

Be it known that we, WILLIAM H. UNKE and OTTO C. UNKE, both citizens of the United States, residing at Milwaukee, in the county of Milwaukee and State of Wisconsin, have invented a new, original, and ornamental Design for Casings for Horn-Blowers, of which the following is a specification, reference being had to the accompanying drawing, forming part thereof.

The figure is a perspective view of a cas-

ing for a horn blower showing our new design.

We claim:

The ornamental design for a casing for horn blowers as shown.

WILLIAM H. UNKE.
OTTO C. UNKE.
